UNITED STATES PATENT OFFICE.

CHARLES B. POTTER, OF CHICAGO, ILLINOIS.

HAIR-DRYING DEVICE.

No. 806,183.

Specification of Letters Patent.

Patented Dec. 5, 1905.

Application filed February 23, 1905. Serial No. 246,883.

To all whom it may concern:

Be it known that I, CHARLES B. POTTER, a citizen of the United States, residing at Chicago, in the county of Cook and State of Illinois, have invented certain new and useful Improvements in Hair-Drying Devices, of which the following is a specification.

My invention relates to improvements in hair-drying devices.

10 The object of my invention is to provide a device adapted to be worn upon the head and over which the hair may be spread for the purpose of being quickly dried.

15 My invention provides, further, a framework adapted to be supported upon the head and provided with an opening through which the hair may be upwardly inserted, a support encircling said opening being provided for the hair upon said framework.

20 My invention provides, further, a flexible and expansible device for supporting the hair and which is adjustable to conform to heads of different sizes and shapes.

25 My invention provides means, further, by which the framework may be locked in the position to which it may be adjusted.

Other novel features are hereinafter fully described and claimed.

30 In the accompanying drawings, Figure 1 is a vertical sectional view taken on the dotted line *a b* of Fig. 2, the individual's hair being represented by the dotted lines. Fig. 2 is a plan view of the hair-drying device. Fig. 3 is an inside elevation view of the jointed ends 35 of the inner ring. Fig. 4 is a plan view showing a network covering connecting the two rings.

Similar characters of reference denote similar parts.

40 In its preferable form the hair-drying device comprises two flexible adjustably-expansible concentric rings 1 and 2, respectively, the outer ring being connected by a supporting means with the inner ring, which

45 supporting means comprises, preferably, one or more radially-disposed arms 3, the inner ends of which are secured to the ring 1 and the outer ends secured to the outer ring 2. Each of the rings 1 and 2 is preferably of 50 flexible material, such as brass or aluminium, thereby permitting flexure of the framework into a shape corresponding to the one desired to fit the wearer's head. Each of the rings is transversely divided and has its overlapping 55 ends adjustable lengthwise of each other, locking means being provided on each ring

for securing together the ends thereof. The following is the preferred form of locking means: One end of each ring is provided with a loop 4, encircling the other end of the ring. 60 A series of holes 5 are provided at intervals lengthwise adjacent one end of the ring, each of said holes being adapted to receive a screw or equivalent device 6, extending through a hole provided in the ring adjacent its other 65 end. On each screw 6 is mounted a nut 7, by the adjustment of which the two ends of the rings may be securely clamped together. To prevent the short hair from falling between the rings 1 and 2, I provide a network 70 8, preferably mounted between the rings and above the arms 3. This network is preferably flexible, so as to conform itself to the shape of the framework. The said network 8 is preferably composed of resilient strands, 75 such as soft rubber, secured, preferably, by sewing them to the rings 1 and 2.

In using my invention the framework is first adjusted to conform to the shape and size of the wearer's head by locating the 80 screws 6 in the proper holes in the rings 1 and 2 and affixing upon said screws the clamping-nut 7. The ring 1 is then placed upon the crown of the wearer's head, the hair being first inserted upwardly through the said inner ring and then spread out over the framework upon the network 8 when such network is employed, the long hairs being permitted to depend from the outer ring. The hair-drying device is then worn in the manner of wearing a hat until such time as the hair has become sufficiently dried, which operation is quickly effected by reason of the spread-out condition of the hair. 85 90

Various modifications of my invention may 95 be resorted to without departing from its spirit.

Having thus described my invention, what I claim, and desire to secure by Letters Patent, is—

1. A hair-drying device comprising two adjustably-expansible rings disposed one within the other, each ring having a locking means for retaining it in its adjusted position, and means for supporting the outer by the inner 105 ring.

2. A hair-drying device comprising two adjustably-expansible rings disposed one within the other, each ring having means for locking it in its adjusted position, and one or more 110 arms connecting said rings.

3. A hair-drying device comprising two ad-

justably-expansible rings disposed one within the other, each ring having means for locking it in its adjusted position, means for supporting the outer by the inner ring, and a flexible network connecting said rings.

4. A hair-drying device comprising two rings disposed one within the other, each ring being transversely divided and having overlapping ends adjustable lengthwise upon each other and having locking means for securing together said ends, and means for supporting the outer by the inner ring.

5. A hair-drying device comprising an inner and an outer ring each having overlapping ends adjustable lengthwise upon each other and having locking means for securing

together said ends, and one or more arms connecting said rings.

6. A hair-drying device comprising two transversely-divided rings disposed one within the other, each having overlapping ends adjustable lengthwise upon each other and having locking means for securing together said ends, means for supporting the inner by the outer ring, and a flexible network connecting said rings.

In testimony whereof I affix my signature in presence of two witnesses.

CHARLES B. POTTER.
